UNITED STATES PATENT OFFICE.

ERNEST H. BENNETT, OF EAST ORANGE, NEW JERSEY, ASSIGNOR TO JOHN H. BROMLEY, JOSEPH H. BROMLEY, AND EDWARD BROMLEY.

DESIGN FOR A RUG.

SPECIFICATION forming part of Design No. 22,211, dated February 14, 1893.

Application filed December 1, 1892. Serial No. 453,793. Term of patent 3½ years.

To all whom it may concern:

Be it known that I, ERNEST H. BENNETT, a citizen of the United States, residing at East Orange, county of Essex, State of New Jersey, 5 have invented and produced a certain new and original Design for a Rug, of which the following is a full, clear, and exact description, reference being had to the accompanying drawing, forming a part of this specification.

My invention relates to the surface ornamentation of a rug and consists of the design therefor shown in the accompanying drawing in which the design is shown as consisting of a comparatively wide leaf-like border A inclosing a rectangular field within which is contained a floral figure B. 15

I claim as my invention,

The design for a rug substantially as shown and set forth.

In testimony whereof I have hereunto affixed my signature this 5th day of July, A. D. 1892.

ERNEST H. BENNETT.
